MANUFACTURE OF FUR COATS AND THE PRODUCT THEREOF

Harry Post, Brooklyn, N. Y.

Application October 16, 1937, Serial No. 169,395

3 Claims. (Cl. 149—28)

This invention relates generally to the manufacture of fur coats, and has particular reference to a novel method of cutting skins of grey Persian lambs and arranging cut strips of such skins and bringing these skins together for the pre-determined purpose of making a novel type of fur garment.

The invention has for its object the provision of a method of cutting and arranging natural grey Persian lamb skins only, for the manufacture of fur coats. A further object of this invention is to produce a novel garment in which these skins alternate in light grey and dark grey longitudinally, with the marginal colors merging into each other.

In the art of furs in which Persian lambs are used, it is known that certain Persian lamb furs are of a predominantly light, approaching white, shade, and the marginal ends of such furs shade into a darker color, approaching dark grey. Certain others of these furs or skins are predominantly dark grey with a gradual shading into lighter color approaching light grey in the centers thereof; and these respective skins are known as light and dark skins. Heretofore, it has been customary to use the light skins to make up a substantially light grey Persian lamb coat and to utilize the dark skins for the manufacture of a dark grey Persian lamb coat. The dark skin coats command higher prices. The light grey skins are considerably lower in price, and light grey skin coats are not popular.

My invention comprehends the utilization of both light and dark skins, and in accordance therewith, I am able to make a Persian lamb coat of longitudinally combined portions alternately arranged in light and dark shades, the general effect being that the coat is made of elongated skins in either light or dark colors, the colors merging together at the margins of the portions. The novelty of my new creation was so marked in the art of fur-making that it has received immediate acceptance by the trade.

With the above and other objects in view, the invention will be hereinafter more fully described and shown in the drawings and finally pointed out in the appended claims.

In the accompanying drawings:—

Figure 1 illustrates the skin side of a piece of light grey fur;

Figure 2 depicts the fur side of a narrow strip of light grey Persian lamb fur;

Figure 3 shows the skin side of light grey fur strips sewed together;

Figure 4 is a skin side view of dark grey Persian lamb fur;

Figure 5 depicts the fur side of a narrow strip of dark grey fur;

Figure 6 shows a skin side view of dark grey fur strips sewed together;

Figure 7 shows the skin side of a piece of fur made by joining the elongated light grey strips such as shown in Figure 3, with the pieces shown in Figure 6, after the pieces such as are shown in Figure 6 have been produced by cutting in two parts, and one of each of the parts joined to the central portion corresponding to that shown in Figure 3;

Figure 8 is a fragmentary sectional view of Figure 7, showing an exterior side of a completed composite piece of fur, having alternate light grey and dark grey pieces of fur joined together; and

Figure 9 shows a complete fur coat made in accordance with my invention.

Similar characters of reference represent similar parts throughout the various views.

Referring to the drawings and more particularly to Figures 1, 2, and 3, a skin 10 of light grey Persian lamb is placed upon a table in the form shown in Figure 1, with the skin side of the skin uppermost. An imaginary line indicated by 11—11 is then drawn through the central portion of the skin, and the skin is then cut into strips angularly downwardly from said median line, as indicated by the lines 15 and 16 on Figure 1. From this preliminary operation there results a series of strips of light grey fur. These are then sewed together in the manner shown in Figure 3, and a piece of light grey fur is produced. It will be noted from Figure 3 that the strips are angularly placed in respect to a median line. These strips were brought together in accordance with the judgment of a skilled furrier who has the ability to compare and select furs of the same color.

A skin 20 of dark grey color is then taken, and a similar operation is carried on; and the resulting piece of dark skin fur is illustrated in Figure 6. An imaginary line 21—21 is drawn through the central portion of the skin shown in Figure 4, and the strips are then cut such as the larger V-shaped cutout 22 and the smaller V-shaped cutouts 23 and 24 and the elongated or narrow strips 27 and 28. These latter strips are angularly disposed in respect to the central line. These strips are then re-arranged in accordance with their curl, and are then joined by sewing so as to form a piece of fur as shown in Figure 6.

The result is that the outer or fur side of the piece shown in Figure 6 is substantially dark in color, representing a dark Persian lamb skin as depicted in Figure 5.

5 The skin shown in Figure 6 is cut longitudinally into halves illustrated by the two parallel lines indicated by reference character *c*, and as a result the two halves indicated by *a* and *b* are obtained.

10 In selecting the strips to make up the pieces shown in Figure 3, the lighter shades of the strips are brought into the central portion, and the darker shades to the marginal portions, all still being light grey fur. In selecting the strips to 15 make the pieces shown in Figure 6, the lighter shades are brought into the central portion, and the darker shades to the marginal portions, all still being a dark grey color.

The pieces of fur shown in Figure 3 are then 20 placed upon a table, and at each side of the piece shown in Figure 3 one of the halves *a* and *b* is placed, and these halves are then joined by a seam to the center portion *A*, as shown in Figure 7, the seams running the whole length of the 25 pieces and indicated by *s*¹ and *s*². The strips bear reference characters resembling those in Figures 3 and 6. When the composite piece shown in Figure 7 is viewed from the exterior or right side, an appearance such as shown in 30 Figure 8 is produced. Pieces such as shown in Figure 7 are then joined together, following selected patterns of ladies' fur coats, and a fur coat such as illustrated in Figure 9 is obtained.

In the final product of a composite piece, the 35 marginal portions of the pieces *a*, *A*, and *b*, merge into each other, the coloring thereof blending one into the other.

About twenty-four skins are necessary to make a coat such as shown in Figure 8. If all the skins 40 would be light grey Persian lamb, the coat would have very little value compared to a coat made only of all dark grey Persian lamb. By utilizing twelve dark grey Persian lamb skins in accordance with this invention, a coat is produced which 45 has the same or a higher sales value than an entirely dark skin coat.

In cutting into the strips in the skin in Figure 1, as also the skin illustrated in Figure 4, certain darker strips such as 17 and 18 may result from the skin of Figure 1, and certain lighter strips may result from Figure 4, as indicated by strips 25 and 26, and these may be preferably merged with the other strips of substantially the same color, so that in working out this improved 55 system it may happen that from the skin shown in Figure 3, certain strips 25 and 26 of lighter color may be utilized from the fur of Figure 4, whereas in the strips shown in Figure 6, certain darker shades of the skin of Figure 1, indicated 60 by 17 and 18, may be utilized.

I have described my invention as embodied in certain forms, but changes may be made therein without departing from the spirit of my invention as defined by the accompanying claims.

I claim:

1. A method of manufacturing Persian lamb furs, which consists in cutting into strips the skin of a light grey Persian lamb which is partially dark, and the skin of a dark grey Persian lamb, which is partially light, selecting all of the light grey strips and joining the same in drop fashion to form a narrow elongated piece of fur substantially of light grey color with the lightest color in the central portion thereof, selecting all of the dark grey strips and joining the same in drop fashion to form a narrow elongated piece of fur substantially of dark grey color with the darkest color in the center thereof, halving the latter, and joining each half at its darker portions to the darker longitudinal margins of the light grey piece of fur to form a composite skin of a light grey central portion and dark grey marginal portions, and joining such composite pieces of fur having dark marginal portions and light central 25 portions to form a garment having longitudinal alternate light and dark bands.

2. A method of manufacturing Persian lamb furs, which consists in joining light grey strips together to form an elongated piece of Persian 30 lamb fur of light grey color with the lighter shades at the central portion and the darker shades at the marginal portion, joining dark grey strips together to form an elongated dark grey piece of Persian lamb fur with the darker 35 shades at the central portion and the lighter shades at the marginal portion, halving the same and then joining the dark grey pieces to the marginal longitudinal portions of the light grey piece to form a composite piece of dark grey having 40 a central light portion, and joining a plurality of such composite pieces together dark edge to dark edge in garment fashion having longitudinal alternate light and dark bands.

3. A garment comprising a plurality of elongated or dropped pieces of fur, alternating in light and dark grey shades, each of said pieces comprising strips of fur joined together, with the lighter fur in the center bounded on each side by darker fur, and all of said strips of each of 50 said skins being substantially the same color with the marginal sections of the adjacent skins resembling each other in color so as to constitute a blending or merger of the colors of one piece 55 of fur into the colors of the other pieces of fur, with alternate light and dark bands, all of said strips being cut from light grey and dark grey Persian lamb skins.
